UNITED STATES PATENT OFFICE.

WILLIAM NELSON, OF NEW YORK, N. Y., ASSIGNEE, BY MESNE ASSIGNMENTS, TO
CONSOLIDATED AMERICAN FASTENER COMPANIES, INC., OF NEW YORK, N. Y.,
A CORPORATION OF NEW YORK.

MACHINE FOR MAKING THE STUD MEMBERS OF SNAP-BUTTONS.

1,358,772.

Specification of Letters Patent. Patented Nov. 16, 1920.

Application filed September 22, 1916. Serial No. 121,622.

To all whom it may concern:

Be it known that I, WILLIAM NELSON, a citizen of the United States, residing in New York, county and State of New York, have invented certain new and useful Improvements in Machines for Making the Stud Members of Snap-Buttons, of which the following is a specification.

This invention relates to the manufacture 10 of one of the parts of the well known snap fastener or press button, which comprises two members, a stud and a socket.

The stud member made by my improved machine consists of a circular base having its 15 edge doubled to provide a thick and smooth periphery and a post which rises from the center of the base and is formed with a head or enlargement at its upper or outer end.

20 The machine for making the stud is adapted to first progressively form in a strip of sheet metal the post, to then form holes in the base to receive the thread which attaches the stud to a garment or fabric, to then form 25 or shape the head on the post, to then emboss on the base the initials of the manufacturer, to then cut the stud blank from the stock and partially turn the edge of the base, and to then flatten said turned edge and thus 30 complete the stud which is then ejected from the machine.

The stock in the form of a metal strip or ribbon is led through a guide from which it passes between a series of sets of upper 35 and lower dies and punches. The first set of dies progressively draws the metal to form the post or shank of the stud, then piercing devices carried by the upper or movable die carrier cut thread holes in the 40 stock close to the post. Then a set of chucks carried by the movable die carrier forms and gives shape to the outer end of the post and after this is done a suitable die on the lower set of dies applies the initials 45 of the manufacturer to the underside of the base portion of the stud. These operations are accomplished before the stud is blanked out, *i. e.*, before the base portion of the stud is separated from the stock. After the initials 50 are applied, another set of dies operates to cut or blank out the stud by separating the base from the stock and at the same time partially turns the edge of the base.

Finally the edge is completely turned and doubled by another set of dies and the stud 55 is thus completed.

The stock is fed step by step between the dies and punches by a novel form of intermittently operated feeding device in such manner that the part of the stock from 60 which each stud is formed is successively operated upon by the different dies and punches until it is gradually drawn, bent or pressed into shape.

In the accompanying drawings: 65

Figure 1 is a perspective view of a stud making machine embodying my invention;

Fig. 2 is a top plan view showing the general arrangement of the lower dies, the head shaping devices and the stock guiding 70 and feeding mechanism;

Fig. 3 shows a side elevation of the parts illustrated in Fig. 2;

Fig. 4 is a top plan view of the stock and shows the successive steps of forming the 75 stud;

Fig. 5 shows a longitudinal section of the stock and different parts of the stud while being formed;

Fig. 6 is a view on an enlarged scale and 80 in vertical section showing the entrance guide for the stock; the notching device, the dies for drawing the metal to form the projection for the post of the stud, the piercing dies and one set of dies for forming the head of the stud; 85

Fig. 7 is a detail view in perspective of the notcher;

Fig. 8 is a similar view with the parts 90 in a different position;

Fig. 9 is a detail plan view on an enlarged scale of the lower dies and coöperating mechanism for giving shape to the heads of the studs, stamping the initials of the manufacturer on the base of the stud, cutting or severing the base from the stock, partially bending the edge of the base and for giving the final bend to the edge portion of the stock. It also shows in plan the stock guiding and feeding mechanism at 100 the exit end of the machine;

Fig. 10 is a detail view, on an enlarged scale, of the upper die members which co-operate with those shown in Fig. 3. It also shows a part of the stock feeding mechanism; 105

Fig. 11 shows a vertical section of the parts illustrated in Figs. 9 and 10;

Fig. 12 is a detail view in vertical section of one of the chucks;

5 Fig. 13 is a detail view, in vertical section, of the upper and lower dies for blanking out the studs and for bending the edges of the stud bases. In Fig. 13 the upper dies are shown in elevated position;

10 Fig. 14 is a view similar to Fig. 13, but showing the upper die partially lowered and in the position it assumes after having blanked out a stud;

15 Fig. 15 shows the position of the dies just after the stud has been blanked out and the edge of the base turned down at right angles to the body of the base;

20 Fig. 16 shows the upper dies in elevated position and illustrates how a slide operates to move the stud from the blanking out dies to the finishing dies;

Fig. 17 shows how the finishing dies operate;

25 Fig. 18 is a perspective view of the finished stud.

The frame Z of the machine may be of any suitable construction. The lower dies are supported on the lower portion of the machine and the upper dies are supported on the upper part thereof and are operated by any suitable mechanism Z¹.

30 The stock in the form of a metal strip or ribbon X is passed through a guide A and between the upper and lower dies and punches to a stock feeder B, which is operated in the manner hereinafter described to pull the stock through the machine between the dies. The entrance guide A comprises a base a to which are attached two 35 grooved guide members a¹, one of which is stationary, while the other is movable sidewise on the base. Said movable member is slotted as indicated at a² and headed screws a³ connect it with the base and limit its sidewise movement. Springs a⁴ tend to draw the movable member toward the stationary one and thus the stock is truly guided without undue pressure or friction.

40 The stock then passes to a device C which progressively cuts out from the metal a small part of the edge portion of the strip to form a shoulder c which engages a part c¹ of the device and limits the forward movement of the stock while being fed. 45 This device insures accuracy of feed, inasmuch as the part c¹ lies in front of the shoulder c during the forward movement of the stock and thus prevents any false movement due to the momentum of the metal or the improper action of the stock feeder. The notcher C comprises upper members C¹ supported by the upper die carrier D and lower members C² supported by the bed plate E. As the upper die carrier descends, the members C¹ cut from one edge of the stock a

small strip of metal forming the shoulder c thus gradually decreasing the width of the strip.

The upper and lower dies and punches for forming the studs are carried by an upper die carrier D and the bed plate E. The upper die-carrier is raised and lowered by any suitable mechanism Z¹ and it is guided by posts F rising from the base and entering sockets F¹ in the die-carrier. 75

The stock is first operated upon by upper and lower dies G G¹ to draw the metal in such manner as to gradually form a projection on the stock which is subsequently shaped to form the headed post of the stud. 80

It will be observed by reference to Fig. 2 that the lower die G¹ is provided with a series of projections g¹, g², g³, g⁴, g⁵, g⁶. The projections are all of the same height but those g¹, g², g³, g⁴, gradually decrease in 85 width, while the projections g⁵, g⁶, are of the same width as the projection g⁴. The upper die G in like manner is provided with a series of depressions g⁷, g⁸, g⁹, g¹⁰, g¹¹, g¹², which coöperate with the projections g¹, etc., 90 to first form a hollow relatively wide projection on the stock and to then gradually reduce its diameter without increasing or decreasing its height. This is done by gradually drawing the metal from the stock and then returning part of the metal thereto. In this way undue strain or breakage of the metal is avoided.

By reference to Fig. 6 it will be observed that the projections g¹, etc., are formed on 100 die bodies which rest on the bed plate E and extend through a block G² and into a stripper G³.

The recesses or depressions g⁷ etc., are formed in die bodies which extend through 105 a block G⁴ attached to the upper die-carrier and into a stripper G⁵. As the upper die-carrier descends, the projections g¹, etc., press the metal into the depressions g⁷, etc., and the posts for the studs are thus formed. 110

After a projection of the proper size is thus produced, the stock is advanced until the projection arrives between the upper and lower punches H, H¹, which pierce the part of the stock which is to form the base 115 of the stud and to thus form holes for the thread by means of which the stud is secured to a garment or to a fabric. The punch member H comprises four rods h and the punch member H¹ is provided with four 120 holes h¹ to receive the rods h. A hole h² is formed in the bed of the machine through which the metal punched out from the stock falls. The member H is provided with a spring pressed stripper h³, of well known 125 construction.

The next operation is to form the head on the projection from the stock. This is done by the upper dies I and the coöperating lower dies I¹. The upper dies are sup- 130

ported by the die-carrier D and the lower dies are supported by the bed E. The upper dies comprise a block *i* attached to the carrier D in which are mounted three sets 5 of formers *i*¹, each set being made in four sections which are free to move laterally to a limited extent. Each set of formers extends down into a stripper I² which is pressed downwardly by springs *i*². The 10 stripper is formed with holes *i*³ into which the formers extend and these holes are reduced in diameter at their lower portion providing inclined walls *i*⁴ with which engage the inclined lower portions *i*⁵ of the 15 formers and cause them to approach each other and form the head on the stud and press it into the required shape. It will be observed that these formers are formed with recesses *i*⁶ for the purpose. The formers 20 coöperate with the mandrels *i*⁷ on the lower dies. Normally the outer ends of the mandrels are disposed below the top of a spring pressed stripper I⁸, but when the upper dies descend the strippers I² and I³ yield. The 25 mandrels enter the projections on the stock and the formers coöperate with the mandrels to give shape to the shank and head of the stud. The first set of dies give the 30 general shape to the head, while the other two complete the operation. It will be observed by reference to Fig. 10, that each set of formers is arranged at a different angle so that the stud is pressed at different parts 35 and thus a smooth product is assured. The parts marked *y* on the stripper and on other parts of the machine are merely recesses to receive the stud when the die descends between shaping operations. In this way the dies may be suitably shaped and sufficiently separated 40 and the required step by step movement of the stock may be performed without crushing the stud. The parts marked *y* are merely guides for centering the dies and any suitable number may be employed. 45 The next operation is to emboss the initials of the manufacturer on the underside of that portion of the stock which is to form the base of the stud. This is done by the dies J and J¹ carried respectively by the die-carrier and the machine base.

Having thus formed the headed post of the stud, it remains to blank out the base thereof, double the edge of the base and eject the completed stud from the machine.

55 From the dies J, J¹, the stock is fed in such manner as to bring the stud blank below a die K and above a die K¹. The die K comprises a block *k* secured to the carrier D and to which is attached a hollow bar or punch *k*¹, which extends through the stripper *k*². Within the punch *k* is a hollow plunger *k*³ mounted to move vertically in the punch and topped by a headed screw *k*⁴ upon which bears a spring *k*⁵ within the punch. The plunger is formed at its lower

end with a head *k*⁶ fitting a recess *k*⁷ in the lower end of the punch and this head carries a vertically movable pin *k*⁸ which is pressed down by a spring *k*⁹. The lower edge *k*¹⁰ of the punch acts as a cutter to 70 sever the stud blank from the stock and it also serves to form a flange on the blank in the manner hereinafter described.

The lower die K¹ comprises a block *l* supported on the bed E and formed with holes 75 to receive springs *l*¹ which support a stripper *l*² mounted in a plate *l*³, which rests on the block *l*. A plate *l*⁴, forming part of the frame supports a die *l*⁵, which coöperates with the punch to sever the stud blank from 80 the stock. M indicates spring pressed jaws which serve to hold the stud blank after it descends with the die K and just before it is transferred to the finishing die. M¹ indicates a mandrel which supports the stud 85 blank after it is severed from the stock and until it is transferred to the finishing die.

The finishing dies are arranged to one side of the line of feed of the stock as indicated in Figs. 2 and 9. The upper die N, 90 Fig. 13, is attached to the block *h*. It comprises a hollow bar carrying a spring pressed stripper pin *n*. The lower end of the bar is formed with an annular peripheral recess *n*¹, which is adapted to coöperate with the 95 lower die to double and flatten down the edge of the base portion of the stud. The lower die N¹ consists of an anvil having in its upper end a recess suitably shaped to receive the stud, and coöperating with the upper die N to give final shape to the stud. A slide O having a bifurcated end *o* is employed for transferring the stud from the die K¹ to the finishing dies N, N¹. This slide, as shown in Figs. 2 and 9, is reciprocated by suitable mechanism P operated in any convenient way. 100

Fig. 13 shows the position of the partially formed stud while still attached to the stock and while resting on the lower die K¹. As 110 soon as the upper die K descends the spring pressed pin *k*⁸ engages the top of the stud but yields and imparts no undue pressure thereto, and then the punch operates to sever the stud from the stock. This is illustrated 115 in Fig. 14. As the punch further descends, the edge of the stud blank is turned down, as indicated in Fig. 15, the stripper *k*² yielding as indicated. When the stud is in this condition, the upper die rises and the stripper also rises and then the stud is held by the jaws M. Immediately after this, the slide O is operated to engage the stud and transfer it to the finishing die N¹ in the manner indicated in Fig. 16. When the dies 120 again descend the upper die N presses the stud against the lower die (Fig. 17) and this turns inward the flange on the blank and doubles it under the base and finally flattens it down beneath the base. 125

The stud is now complete and it is removed from the finishing dies by a blower Q of any suitable construction. The outer end of the blow pipe q is arranged in front of the die N^1 and the stud is blown against a hood or shield R and then drops through a hole r . The valve of the blowing apparatus is indicated at q^1 and this is opened on the up stroke of the press, by a cam q^2 pivoted to an arm q^3 depending from the die-carrier D . The cam is drawn in one direction by a spring q^4 , which allows the cam to yield and pass the valve without operating it on the down stroke, but on the up stroke of the die-carrier the valve is opened by the cam as will be clear from an inspection of Fig. 3 of the drawings.

The upper die may be raised and lowered in any suitable way, as indicated at Z^1 , Fig.

- 20 1. The stock is preferably fed through the machine by the feed mechanism shown, particularly in Figs. 3 and 11. There are two levers S and T , pivotally connected with each other at s . These levers have co-operating jaws s^1 , t^1 , adapted to engage the stock. The lower lever T is pivoted to the base at t and it is provided with a brake U which resists to some extent its pivotal movement. The upper lever is provided with a roller operating in a cam slot v in a cam plate V attached to the upper die-carrier. The arrangement is such that when the cam is lowered the jaws are opened, but when the cam ascends the jaws close, grasp the stock and feed it forward a single step. On the downward movement of the cam, the upper lever moves slightly independently of the lower one and then the two levers swing forward together. On the return movement the operation is reversed. The upper lever first swings independently of the lower one, the stock is grasped and the two levers then swing together. In order to regulate the movement of the levers and also to regulate the feed of the stock, I employ a stop W consisting of a frame piece w carrying an adjustable screw w^1 . The stock passes to the feeder below a guide spring W^1 which prevents the stock from rising, buckling or moving backward during the inward movement of the feeder.

It will be understood that the feed of the stock is also regulated and made certain by the notcher C which forms the shoulders on the edge of the stock and prevents the overthrow thereof while being fed.

Figs. 4 and 5 illustrate the different steps of the operation of the dies on the stock. The parts 1, 2, 3, 4, 5 and 6 are formed successively by the dies g^1 , etc. 7 indicates a part which is not operated upon by the dies. 8 indicates where the thread holes are formed. 9, 11, 13 and 15 indicate parts not operated upon by the dies, while 10, 12 and

14 show where the head of the stud is produced. 16 indicates where the initials of the manufacturer are applied. 17 and 18 indicate parts not operated upon by the dies and 19 indicates where the stud is cut or blanked out from the stock. By comparing the diagrammatic views shown in Figs. 4 and 5 with the different sets of dies, etc., before described, the manner in which the stud is produced will be clearly understood.

The machine thus constructed is simple and efficient and operates to deliver the completed studs in rapid succession. It will be understood that while one stud is being completed, other studs are in process of formation, and while a number of operations are required to complete a stud, there is no loss of time inasmuch as the mechanism is so organized as to perform each operation while all the other operations are taking place.

I claim as my invention:

1. In a stud making machine, the combination of the machine bed, a vertically movable upper die-carrier supported by the bed, a stock guide at the entrance end of the machine, a stock feeder at the exit end thereof, means operated by the movement of the upper die-carrier for actuating the stock feeder, a guide for the stock close to the stock feeder and in advance thereof, and co-operating dies carried by the bed and the upper die-carrier for first forming the headed post of the stud, then blanking it out and then finishing the base by doubling and flattening the edge portion thereof.

2. In a stud making machine, the combination of the machine bed, a vertically movable upper die-carrier supported by the bed, a stock guide at the entrance end of the machine, an intermittently actuated stock feeder, co-operating dies carried by the bed and the upper die-carrier for forming the stud, and a punch actuated by the upper die-carrier for forming a shoulder on the stock to limit the advance movement thereof while being fed.

3. In a stud making machine, the combination of the machine bed, a vertically movable upper die-carrier, means for advancing the stock step by step between the bed and the carrier, means for forming a headed projection on the stock, companion dies for blanking out the stud from the stock and for bending the edge portion thereof, companion dies for doubling and flattening said edge portion, and means movable transversely to the line of stock feed for transferring the stud from the blanking out dies to the doubling dies.

4. In a stud making machine, the combination of the machine bed, a vertically movable upper die-carrier, means for advancing the stock step by step between the bed and the carrier, means for forming a head-

- ed projection on the stock, companion dies for blanking out the stud from the stock and for bending the edge portion thereof, companion dies for doubling and flattening 5 said edge portion, means movable transversely to the line of stock feed for transferring the stud from the blanking out dies to the doubling dies, and a blower actuated by the die-carrier for removing the completed stud from the doubling die.
5. In a stud making machine, the combination of the machine bed, a vertically movable upper die-carrier, means for advancing the stock step by step between the bed 15 and carrier, means for forming a headed projection in the stock, companion dies for blanking out the stud from the stock and for bending the edge portion thereof, spring jaws for holding the stud in place after being bent, companion dies for doubling and flattening the edge portion of the base, and means movable transversely to the line of stock feed for transferring the stud from said jaws to the doubling dies.
- 20 6. In a stud making machine, the combination of the machine bed, a vertically movable upper die-carrier, coöperating dies on the bed and the carrier for forming the stud and separating it from the stock, and a stock feeder comprising a lower lever pivotally connected at its lower end to the base and having a stock gripping jaw, an upper lever pivotally connected with the upper end of the lower lever and having a stock gripping jaw, and a cam operated by the upper die-carrier for actuating the levers.
- 25 7. In a stud making machine, the combination of the machine bed, a vertically movable upper die-carrier, coöperating dies on the bed and carrier for forming the stud and separating it from the stock, and a stock feeder comprising a lower lever pivotally connected at its lower end to the base and having a stock gripping jaw, an upper lever 30 pivotally connected with the upper end of the lower lever and having a stock gripping jaw, a cam carried by the upper die-carrier for operating the levers, and an adjustable stop for limiting the movement of the upper lever relatively to the lower one.
- 35 8. A stud making machine comprising means for feeding a strip of stock, a series of dies to operate upon the stock to draw the metal therefrom to form a post, means for reducing the breadth of the post with- 40 out increasing or decreasing the length of the same by returning part of the metal of the post to the stock, means for forming a head upon the post, means for blanking the post from the stock strip and for simultaneously bending the edge of the metal thus blanked, and means for curling over and bending down the said bent edge.
- 45 9. A stud making machine comprising means for operating upon the stock to form a post thereon, means for blanking the post from the stock and for bending the edge of the blanked portion while carried by said blanking means, and means for operating upon the said bent edge to curl the same upon the under face of the blanked portion.
- 50 10. In a stud making machine, a bed, a die carrier movable toward and away from the bed, a stock feeder on the bed, and means actuated by the said die carrier for operating the feeder to feed the stock.
- 55 11. In a stud making machine, a bed, a die carrier movable toward and away from the bed, a stock feeder comprising upper and lower levers pivoted together at their adjacent ends and providing stock gripping jaws, one of said levers being pivoted to the bed, and a cam and slot connection between the other of said levers and the die carrier.
- 60 12. In a machine of the character described, means for successively operating upon the stock to provide a post, means for blanking the stock around the post and for bending the edge of the base thus formed, clamping jaws for yieldably holding the base, doubling dies for operating upon said bent edge, and means for transferring the said base from the jaws to the doubling dies.
- 65 13. In a stud making machine, means for successively operating upon the stock to form a post, coöperating head forming dies to reduce the breadth of the post below the upper end thereof, means for blanking the stock around the post, clamping jaws for the stud doubling dies, and means for transferring the stud from the said clamping jaws to the said doubling dies.
- 70 In testimony whereof, I have hereunto subscribed my name.
- WILLIAM NELSON.
